ELECTRIC HAND DRIER

Saul Birnbach, Flushing, N. Y.

Application June 9, 1955, Serial No. 36,438

Term of patent 3½ years

(Cl. D4—3)

FIG. 1

FIG. 3

Fig. 1 is a perspective view of an electric hand drier showing my new design;

Fig. 2 is a right hand end view thereof; and

Fig. 3 is a bottom view thereof.

I claim:

The ornamental design for an electric hand drier, substantially as shown.
